UNITED STATES PATENT OFFICE.

CHARLES A. CONGER, OF OAKLAND, CALIFORNIA.

DESIGN FOR A CONDIMENTS-SHAKER.

43,668.

Specification for Design.

Patented Mar. 4, 1913.

Application filed June 26, 1912. Serial No. 706,094. Term of patent 14 years.

To all whom it may concern:

Be it known that I, CHARLES A. CONGER, a citizen of the United States, residing at Oakland, in the county of Alameda and State of California, have invented a new, original, and ornamental Design for Condiment-Shakers, of which the following is a specification, reference being had to the accompanying drawings, forming part thereof.

Figure 1 is an elevation of the condiment shaker, showing my new design. Fig. 2 is a bottom view of the condiment shaker. Fig. 3 is a top view of the condiment shaker. Fig. 4 is an elevation of the condiment shaker taken at right angles to Fig. 1.

I claim:

The ornamental design for a condiment shaker, as shown.

CHARLES A. CONGER.
